UNITED STATES PATENT OFFICE.

JOSEPH MANN, OF PHILADELPHIA, PENNSYLVANIA, ASSIGNOR TO UNION SPECIAL MACHINE COMPANY, OF CHICAGO, ILLINOIS, A CORPORATION OF ILLINOIS.

PULL-OFF FOR SEWING MACHINES.

Application filed June 1, 1927. Serial No. 195,732.

The invention relates to new and useful improvements in pull-offs for sewing machines, and more particularly to a means for pulling thread from the supply when the 5 presser foot is raised.

An object of the invention is to provide a device for engaging the needle thread and pulling a certain amount of thread from the supply when the presser foot is raised, which 10 device includes means for automatically releasing the thread while the presser foot is still raised.

A further object of the invention is to provide a device of the above character which 15 pulls not only needle thread, and looper thread from the supply, but releases the thread drawn off while the presser foot is still raised.

A further object of the invention is to provide means of the above character wherein 20 the releasing means for releasing the thread drawn off is automatically operated by the raising of the presser foot, and wherein the time of release may be varied for varying 25 the amount of thread drawn off.

These and other objects will in part be obvious and will in part be hereinafter more fully disclosed.

In the drawings which show by way of 30 illustration one embodiment of the invention—

Figure 1 is a front view of a portion of a sewing machine having my improvements applied thereto;

Fig. 2 is a rear view of the same;

Fig. 3 is a view partially in section and partially in broken lines from the rear, showing the threads as drawn off and the devices 40 released for giving up thread;

Fig. 4 is a view in perspective showing a portion of the pull-off device and the adjustable cam for releasing the pull-off members; and

Fig. 5 is a detail showing in perspective

a portion of the link of the pull-off device and the latch which cooperates therewith.

The invention is directed broadly to a pull-off for sewing machines for pulling the needle thread and also the looper thread from 50 the supply when the presser foot is raised.

This is accomplished by a rock lever having an arm which engages the needle thread so that when the rock lever is oscillated, a needle thread will be pulled from the supply, 55

the amount of thread pulled depending the extent of movement of the arm. A second arm is connected to the rock lever so as to move therewith, and this second arm is pro- 60

vided with a device for engaging the looper thread and pulling a certain amount of looper thread from the supply, depending upon 65

the extent of movement of the rock lever. The rock lever is connected to a rock frame 70

which in turn is connected to the presser bar. The connection between the rock lever and 75

the rock frame includes a telescoping link and latch for holding the parts of the link in rigid fixed relation to each other. When 80

the parts are latched together, and the presser foot is raised, the rock arm will be oscil- 85

lated and needle thread will be drawn from the supply, and likewise looper thread drawn 90

from the supply. When a proper amount of thread is drawn, the latch is automatically 95

released, and this releases the telescoping parts of the link, and the spring returns 80

the rock arm to its normal position, thus giving up the thread drawn off. This occurs while the presser foot is still raised. 85

Referring more in detail to the drawings, my invention is shown as applied to a sewing machine having a standard 1 carrying an overhanging arm 2 and a cylindrical work supporting arm 3. At the outer end of the 85

overhanging arm 2 is a needle bar 4 carrying needles 5, 5. Cooperating with the needles in the work supporting cylinder is a thread carrying looper. The needles are supplied 90

with the threads n, n' . There is a looper co-

operating with each needle, and the loopers are supplied with looper threads l, l' .

The needle bar 4 is reciprocated by a needle lever 6. Associated with the needle lever 5 are thread guides 7 and 8 for the needle threads. On the upper end of the needle bar is a needle thread guide 9. The material is held on the work support by a presser foot 10 carried by the presser bar 11. The presser bar 10 is adapted to be raised by means of a lever 12 pivoted at 13 to the overhanging arm 2. The forward end of the lever extends beneath the projecting lug 14 on the presser bar. A spring 15 presses on said lug and holds the presser bar in its lowered position. When the lever 12 is oscillated, the presser bar will be raised. Mounted on the lever 12 is an arm 16 which, together with the lever 12, forms a rock frame. Mounted on the overhanging arm 2 of the machine is a rock arm 17. This rock arm 17 is mounted on a stud 18 secured to the overhanging arm 2 by a set screw 19. The rock arm 17 is, in reality, provided with two arms, one of which is substantially horizontal, and the other vertical. The horizontal arm carries a plate 20 which is secured to the horizontal arm by screws 21, 21. The plate 20 is provided with a bracket 22 which extends outwardly, thence laterally at 23, thence downwardly at 24, thence laterally again and upwardly at 25, forming a hook-shaped end adapted to engage the needle threads, as clearly shown in Fig. 3 of the drawings. This hook-shaped end of the bracket 22 engages the needle threads between the thread guide 8 on the needle lever and the thread guide 26 carried by a lever 27^a which has connection with the presser bar. It will readily be seen that when the rock arm is oscillated, the hook-shaped end of the bracket 22 will engage the needle threads, and as this hook-shaped end moves away from the thread guides 8 and 26, it will draw thread through the thread guide 8 and the tensions 27, 27 from the supply.

The rock arm 17 is provided with a sleeve hub 28, and an arm 29 is secured thereto. This arm 29 oscillates with the rock arm 17. The arm 29 is connected to a rod 30. This rod extends down alongside the standard 1 and slides vertically in a bracket 31. The rod is provided with an arm 32 which projects laterally from the rod, thence upwardly at 33, where it is slightly offset and bent downwardly at 34. This forms a hook-shaped bracket arm which engages the looper threads l, l' , between the guide tube 35 and the tension 36 shown in broken lines in Fig. 3 of the drawings. A spring 37 is attached to the bracket 31 and to the rod 30, and normally tends to raise the rod 30 to bring the upper hooked end slightly above the path of normal travel of the looper threads. When the rod is depressed, said hooked end will move away from the guide 35 and pull the looper

thread from the supply. The amount of thread drawn from the supply depends upon the extent of movement of the rod 30. The spring 37 will return the rod to its normal position, and thus give up the thread drawn off when the rod is released. The same is true of the needle threads. The oscillation of the rock arm 17 which moves the rod 30 to cause the looper threads to be drawn from the supply, also draws the needle threads from the supply, and the spring which returns the rod 30, so as to give up the thread drawn off, returns the rock arm and gives up the needle thread.

The rock arm is oscillated by a link connection with the arm 16 attached to the presser foot lifting lever. The link is a telescoping link, formed of two sections 38 and 39. The section 39 is provided with a recess 40 which forms the end of the section into a sleeve, and the section 38 slides within this sleeve. The section 38 is provided with a notch 41. The sleeve part of the section 39 is provided with spaced upstanding lugs 42, between which is pivoted a latch 43. The latch 43 has the end 44 thereof extended at right angles, and shaped to engage and fit the notch 41. A spring 45 normally holds the latch pressed against the section 38, and seated in the notch when the notch is positioned within the sleeve so as to receive the end 44 of the latch. The sleeve is provided with an opening through which the end 44 of the latch extends to engage the notch. When the parts of the link are latched together, then the downward movement on the left-hand end of the presser bar lifting lever, as viewed in Fig. 2, will move the arm 16 in a counter-clockwise direction, and this, through the link, will oscillate the rock arm 17 in a counter-clockwise direction, causing needle thread to be drawn from the supply, and also causing looper thread to be drawn from the supply. This drawing of the threads from the supply occurs, therefore, at the time when the presser foot is raised. It is desired to remove the fabric from the machine while the presser foot is still raised, and therefore, it is an advantage to give up this thread drawn off to permit the removal of the fabric and a proper amount of thread to be drawn through the eyes of the needles and the eyes of the loopers, so that when the threads are severed, there is ample supply of thread to insure a stitch formation when the stitching of the next article begins.

In order that the thread drawn off may be given up while the presser foot is raised, I have provided the plate 20 of the rock arm 17 with an adjustable releasing cam 46. Said releasing cam 46 is pivoted at 47 to the plate 20. The releasing cam is provided with a slot 48 through which a screw passes which is threaded into the plate 20. This permits the cam to be shifted on the plate 20. The

latch 43 is provided with a projecting arm 49. When the rock arm 17 is oscillated, the releasing cam 46 moves therewith. The oscillating movement of the rock arm which 5 draws thread from the supply, brings this releasing cam into contact with the arm 49 of the latch, and will lift the latch. When the latch is lifted, then the section 38 is released from the section 39. The recess 40 is 10 of sufficient length so as to permit the section 38 to move further into the section 39. This movement of the rock arm 17 is brought about by the spring 37.

When the presser bar is raised, the pull-off 15 device will be operated to pull thread from the supply, and this pull-off device will also be automatically released from the presser bar lifting means, so that the spring may return the pull-off devices to their normal position and thus give up the amount of thread 20 drawn off. This, of course, takes place while the presser foot is still raised. The time of release can be varied by adjusting the position of the releasing cam, and therefore, the 25 amount of thread drawn off can be varied by adjusting the releasing cam.

It is obvious that minor changes in the details of construction and the arrangement of the parts may be made without departing 30 from the spirit of the invention as set forth in the appended claims.

Having thus described the invention, what I claim as new and desire to secure by Letters Patent, is—

35 1. In a sewing machine, the combination of a needle, a presser foot, and means for raising said presser foot and pulling needle thread from the supply, said means including devices for automatically releasing the thread 40 pulled off while the presser foot is still raised, said automatic releasing devices being adjustable whereby the amount of thread drawn off may be varied.

2. In a sewing machine, the combination of 45 a needle, a thread carrying looper cooperating with said needle, a presser foot, and means for raising said presser foot and pulling needle thread and looper thread from the supply, said means including devices for automatically releasing the thread pulled off while 50 the presser foot is still raised, said automatic releasing devices being adjustable whereby the amount of needle thread and looper thread drawn off may be varied.

55 3. In a sewing machine, the combination of a needle, a presser foot, a lever for lifting said presser foot, a rock frame oscillated thereby, a rock arm, means actuated by said rock arm for pulling needle thread from the supply and 60 pulling looper thread from the supply, devices for connecting said rock frame and said rock arm, said devices including a releasable means whereby said rock arm may be released from its connection to the rock frame and the 65 amount of thread drawn off given up while

the presser foot is still raised, and an adjustable releasing cam for releasing the connection between the rock frame and the rock arm.

4. In a sewing machine, the combination of 70 a needle, a presser foot, a lever for lifting said presser foot, a rock frame oscillated thereby, a rock arm, means actuated by said rock arm for pulling needle thread from the supply and pulling looper thread from the supply, devices for connecting said rock frame and 75 said rock arm, said devices including a releasable means whereby said rock arm may be released from its connection to the rock frame and the amount of thread drawn off given up while the presser foot is still raised, an adjustable releasing cam for releasing the connection between the rock frame and the rock arm, and a spring for returning the rock arm to 80 normal position when released.

5. In a sewing machine, the combination of 85 a needle, a thread carrying looper, a presser foot, a presser foot lifting lever, an arm carried thereby forming a rock frame, a rock arm, a bracket connected to said rock arm and adapted to engage the needle thread for drawing 90 thread from the supply when said rock arm is oscillated, a rod connected to the rock arm, a bracket carried by the rod and adapted to engage the looper thread for drawing thread from the supply when the rock arm 95 is oscillated, releasable devices for connecting the rock frame and the rock arm, said releasable devices including a link having telescoping parts, a latch carried by one part and adapted to engage the other for holding the 100 parts in rigid connection, whereby when the presser foot is raised, the rock arm will be moved for drawing threads from the supply, an adjustable cam carried by the rock arm adapted to engage the latch and release the 105 latch when the proper amount of thread is drawn from the supply, and a spring for returning the rock arm to normal position when released from the rock frame, thus giving up 110 the thread drawn from the supply while the presser foot is still raised.

6. In a sewing machine, the combination of 115 a needle, a presser foot, a lever for lifting the presser foot, a rock frame oscillated thereby, a rock arm for pulling needle thread from the supply, a sectional link for connecting said rock arm to said rock frame, latching means for connecting the sections of said link, and means for releasing the latch while the presser foot is still raised.

7. In a sewing machine, the combination of 120 a needle, a presser foot, a lever for lifting the presser foot, a rock frame oscillated thereby, a rock arm for pulling needle thread from the supply, a sectional link for connecting said rock arm to said rock frame, latching means for connecting the sections of said link, and adjustable means for releasing the latch while the presser foot is still raised.

8. In a sewing machine, the combination of 125

a needle, a presser foot, a lever for lifting the presser foot, a rock frame oscillated thereby, a rock arm for pulling needle thread from the supply, a sectional link for connecting said rock arm to said rock frame, latching means for connecting the sections of said link and means for releasing the latch while the presser foot is still raised, said latch operating automatically to connect said sections when the presser foot is lowered.

In testimony whereof, I affix my signature.
JOSEPH MANN.
